UNITED STATES PATENT OFFICE.

KARL SCHMUTZ, OF NEW YORK, N. Y.

FABRIC-WORKING IMPLEMENT.

Application filed December 16, 1924. Serial No. 756,353.

To all whom it may concern:

Be it known that I, KARL SCHMUTZ, a citizen of the United States, and resident of New York, in the county of New York and State of New York, have invented certain new and useful Improvements in Fabric-Working Implements, of which the following is a specification.

The invention relates to fabric working implements in which the materials used may be conveniently supported for manual operation.

More particularly the invention relates to means for securely holding scarfs or other fabrics, together with the necessary thread or yarn therefor, whereby the fabrics may be manually fringed or otherwise ornamented.

An object of the invention is to provide means for suitably holding both the fabric and the thread in adjustable relation with each other.

A further object is to provide a clamp arranged to yieldingly engage the fabric with sufficient tension to hold the latter against displacement, and also to provide a detachable resilient locking means therefor that may be quickly operated.

For further comprehension of the invention, and of the objects and advantages thereof, reference will be had to the following description and accompanying drawing, and to the appended claims in which the various novel features of the invention are more particularly set forth.

Figure 1 of the drawing is a top plan view of the combined clamp and thread holder embodying the present invention; Figure 2 is a side elevation of the same with the upper portion of the thread holder removed; Figure 3 is a detail view of the thread holder; Figure 4 is an enlarged view of the clamping latch; and Figure 5 is a sectional view taken on the line 5-5 of Figure 4.

In the drawings numeral 10 designates a suitable base plate arranged to serve as a member against which the fabric or material operated upon is clamped, and upon this plate is secured a hinge member 11 having a projecting leg provided with a hinge-pin 12, the hinge member being secured to the plate by the screws 13.

Pivottally secured at one end by the hinge-pin 12, is a clamp bar 14, the opposite or free end of which is shaped to form a pair

of spaced convex clamping jaws 15, provided with stop grooves 16. The clamp bar 14 is further provided with a resilient clamping face 17 preferably of soft rubber.

Adjacent the free end of the clamp bar is a latch plate 18, secured to the base plate 10 by the screws 19, the latch plate 18 having a pair of spaced hinge-projections 20 provided with a pin 21, the latter being pivotally connected to the lower end 22 of the spring-rod 23. Adjacent its lower end the spring-rod is provided with an enlarged head 24 forming at its upper end a shoulder 25 which is adapted to engage as a stop a side edge of the bearing formed in the screw-cap 26. The latter is provided at its upper end with a screw-thread which engages a correspondingly threaded lower end of a tubular grip member 27, which latter at its upper end is formed with a pair of finger-grips 28. Surrounding the spring-rod 23 is a helical compression spring 29, the opposite ends of which bear respectively against the opposite side edge of the bearing formed in the screw-cap and a guide flange 30 fixed to the free end of the spring-rod 23. As thus mounted the inner wall of the tubular grip member 27 is slidably engaged by the flange 30 and the spring-rod 23 is slidable within the bearing of the screw-cap 26, the latter being also provided with a pair of oppositely projecting latch arms 31, having V-shaped projections 32 disposed to engage the stop-grooves 16 formed in the jaws 15 of the clamp bar 14.

Under action of the spring 29 the inward movement of the spring-rod 23 is limited by the shoulder thereof, and on the pivotal connection pin 21 of the latch-plate 18 the rod in its assembled relation with the grip member 27 is adapted to swing for detachable engagement with the jaws 15 of the clamp-bar 14. In its clamping engagement the grip member 27 is manually raised against the action of the spring by means of the finger-grips 28 and is then swung into the vertical position shown in Figure 2, the latch-arms 31 and projections 32 sliding over the convex surfaces of the jaws to urge and hold the spring under compression as the projections on the arms enter the stop-grooves 16.

By suitably proportioning the strength of the spring 29 the desired clamping action may be effected between the base-plate 10

and the face 17 of the clamp member 14 for holding the fabric or work under necessary tension.

For adjustably holding the thread with respect to the fabric a thread-bar 33 is provided, having bent portions 34 and 35 constituting supporting members, the latter one 35 serving as a hinge member pivotally mounted in the clip 36, fixed to the base 10 by one of the screws 13, the bar 33 being disposed in a substantially horizontal position and adapted to loosely support one or more spools of thread or yarn.

In operation the grip member 27 is swung clear of the clamp bar 14, which latter is then raised and the scarf or fabric to be operated upon laid upon the base plate 10. The clamp bar is then lowered and its free end engaged by the grip member, a comparatively light spring action of the latter only being required to effect the necessary clamping action by reason of the resilient rubber facing 17 which engages the work and protects it against injury.

In its working position the portion of the fabric operated upon overhangs in clear relation the clamping members, and the thread is manually drawn from a spool carried by the bar 33 and introduced in well-known manner into and through the fabric by a conventional needle.

What I claim as my invention and desire to secure by Letters Patent, is:

1. A fabric working implement comprising a base, a clamp bar hinged at one end to said base and provided at its opposite end with a convex clamping jaw, and a grip member pivotally connected to the base and adapted to swing inwardly to engage the convex jaw and effect the clamping action of the bar.

2. A fabric working implement comprising a base, a clamp bar hinged at one end to said base and provided at its opposite end with a convex clamping jaw, and a grip member pivotally connected to said base and adapted to swing inwardly to engage the convex jaw and effect the clamping action of said bar, the said grip member being resilient with respect to its pivotal connection.

3. A fabric working implement comprising a base, a clamp bar hinged at one end to

said base and provided at its opposite end with a clamping jaw, and a grip member adapted to engage the clamping jaw of said bar and exert a clamping action between the latter and said base, the said grip member being pivotally connected to said base.

4. A fabric working implement comprising a base, a clamp bar hinged at one end to said base and provided with a resilient clamping face, and a grip member detachably engaging the free end of said clamp bar and adapted to effect a clamping action between the latter and said base, the said grip member being pivotally connected to said base.

5. A fabric working implement comprising a base, a clamp bar hinged at one end to said base and provided at its opposite end with a clamping jaw, and a spring acting grip member adapted to engage the clamping jaw of said bar and exert a resilient clamping action between the latter and said base, the said grip member being pivotally connected to said base.

6. A fabric working implement comprising a base, a clamp bar hinged at one end to said base and provided at its opposite end with a clamping jaw having a stop-groove therein, and a spring acting grip member disposed to engage the stop-groove of said clamping member and exert a clamping action between said clamp bar and said base, the said grip member being pivotally connected to said base.

7. In a fabric working implement including a clamp-bar therefor, a tubular grip member, a cap detachably connected to one end of said grip member, a spring-rod slidable in said cap and extending into said tubular grip member, a spring enclosed within said grip member and surrounding said spring-rod, connections between said spring and spring-rod whereby the latter is inwardly urged within said grip member, and means connecting the outer end of said spring-rod whereby the grip member is adapted to exert a clamping action upon said clamp-bar.

Signed at New York, in the county of New York and State of New York this 13th day of December A. D. 1924.

KARL SCHMUTZ.
